UNITED STATES PATENT OFFICE.

PETER F. BEAULIEU, OF BEND, OREGON, ASSIGNOR OF ONE-HALF TO E. C. LANDINGHAM, OF BEND, OREGON.

DESIGN FOR A MOTORMETER.

58,698.

Specification for Design.

Patented Aug. 30, 1921.

Application filed April 28, 1921. Serial No. 465,228. Term of patent 7 years.

To all whom it may concern:

Be it known that I, PETER F. BEAULIEU, a citizen of the United States, and a resident of Bend, in the county of Deschutes and State of Oregon, have invented a new, original, and ornamental Design for a Motormeter, of which the following is a specification, reference being had to the accompanying drawings, forming part thereof.

Figure 1 is a view in front elevation.

Fig. 2 is a view in rear elevation showing my new design.

I claim:

The ornamental design for a motormeter substantially as shown.

PETER F. BEAULIEU.
